Patented Dec. 25, 1923.

Des. 63,666

UNITED STATES PATENT OFFICE.

JOSEPHINE F. STEWART, OF WASHINGTON, DISTRICT OF COLUMBIA.

DESIGN FOR A SACHET BAG OR SIMILAR ARTICLE.

Application filed July 24, 1923. Serial No. 6,851. Term of patent 14 years.

To all whom it may concern:

Be it known that I, JOSEPHINE F. STEWART, a citizen of the United States, residing at Washington, in the District of Columbia, have invented a new, original, and ornamental Design for Sachet Bags or Similar Articles, of which the following is a specification, reference being had to the accompanying drawing, forming a part thereof.

The figure is a face view of a sachet bag or similar article, showing my new design.

I claim:

The ornamental design for a sachet bag or similar article, as shown.

JOSEPHINE F. STEWART.
